US00D968626S

(12) **United States Design Patent** (10) **Patent No.:** **US D968,626 S**
(45) **Date of Patent:** **** Nov. 1, 2022**

(54) **MEDICAL COOLING DEVICE**

(71) Applicant: **RECENS MEDICAL, INC.**, Ulsan (KR)

(72) Inventors: **Gun Ho Kim**, Ulsan (KR); **Dae Hyun Kim**, Hwaseong-si (KR); **Ho Young Joo**, Goyang-si (KR); **Eun Ho Kim**, Seoul (KR)

(73) Assignees: **RecensMedical, Inc.**, Ulsan (KR); **UNIST (Ulsan National Institute of Science and Technology)**, Ulsan (KR)

(**) Term: **15 Years**

(21) Appl. No.: **29/760,757**

(22) Filed: **Dec. 3, 2020**

(30) **Foreign Application Priority Data**

Aug. 7, 2020 (KR) 30-2020-0036853

(51) **LOC (13) Cl.** **24-01**

(52) **U.S. Cl.**

USPC **D24/200**; D24/206

(57) **CLAIM**

The ornamental design for a medical cooling device, as shown and described.

DESCRIPTION

FIG. 1 is a perspective view of a medical cooling device according to an embodiment.

FIG. 2 is a front view of the medical cooling device of FIG. 1.

FIG. 3 is a rear view of the medical cooling device of FIG. 1.

FIG. 4 is a left side view of the medical cooling device of FIG. 1.

FIG. 5 is a right side view of the medical cooling device of FIG. 1.

FIG. 6 is a top plan view of the medical cooling device of FIG. 1; and,

FIG. 7 is a bottom plan view of the medical cooling device of FIG. 1.

The broken lines illustrate portions of the medical cooling device that form no part of the claimed design.

1 Claim, 7 Drawing Sheets
